United States Patent Office

Des. 188,129
Patented June 7, 1960

188,129

CAP FLASHLIGHT OR SIMILAR ARTICLE

Morris H. Wansky, 627 Fernwood Drive; Robert G. Hudak, 753 Marie Ave.; and Michael P. Mitchin, 4016 Lake Vista Road, all of Akron, Ohio

Filed Jan. 22, 1959, Ser. No. 54,265

Term of patent 14 years

(Cl. D48—24)

FIG. 1

FIG. 2

FIG. 3

FIG. 4

Fig. 1 is a top plan view of a cap flashlight or similar article showing our new design;
Fig. 2 is a front elevation thereof;
Fig. 3 is a bottom plan thereof; and
Fig. 4 is a left side elevation thereof.
We claim:

The ornamental design for a cap flashlight or similar article, as shown.
